UNITED STATES PATENT OFFICE.

LEOPOLD SANDERS, OF NEW YORK, N. Y.

IMPROVEMENT IN HOOP-SKIRTS.

Specification forming part of Letters Patent No. 40,363, dated October 20, 1863.

To all whom it may concern:

Be it known that I, LEOPOLD SANDERS, of the city, county, and State of New York, have invented a new and useful Improvement in Skeleton or Hoop Skirts; and I do hereby declare that the following is a full, clear, and exact description of the same, reference being had to the accompanying drawings, making a part of this specification, in which—

Figure 1 is a side view of a skirt constructed according to my invention; Fig. 2, an enlarged view of a portion of the same; Fig. 3, a detached perspective view of a clasp pertaining to the same; Fig. 4, a section of the same, taken in the line $x x$, Fig. 2.

Similar letters of reference indicate corresponding parts in the several figures.

This invention relates to a new and improved means for securing the hoops of the skirt to the tapes, whereby a very firm and strong connection is obtained between the parts aforesaid and all shifting or moving of the same out of their proper or relative position effectually prevented.

To this end the invention consists in the employment or use of braids or cords, in connection with metallic clasps arranged and applied in the manner substantially as herein-after set forth.

To enable those skilled in the art to fully understand and construct my invention, I will proceed to describe it.

A represents the waistband of the skirt; B, the tapes, and C the hoops. These parts may be constructed in the ordinary way and of the usual materials.

The hoops C are attached to the tapes B, as follows:

D represents clasps constructed of sheet-metal and provided with spurs or prongs a , which are pushed through the tapes and clinched at their inner sides, the clasps encircling the hoops, as shown in Fig. 4. The form of these clasps is shown clearly in Fig.

3. These clasps have each a hole, b , made in them to admit of braids or cords c being passed through them. The braids or cords are passed through the holes b , through the tapes B, around the hoops C, and back through the holes b , as shown in Fig. 4, the braids or cords being crossed from one clasp to the one immediately above and below it, there being two clasps applied to each hoop on each tape, as shown clearly in Fig. 2. The braids or cords are passed through the clasps and tapes and around the hoops, and drawn tightly around the latter, and the spurs or prongs a then clinched, which binds the parts firmly and secures them to ether, effectually preventing the hoops and tapes from shifting their position.

Braids or cords have been previously used and crossed in the same way on the tapes, as herein shown and described, but they have been simply passed through the tapes around the hoops and then back again through the tapes, and the needle passed through the braids or cords where they first passed through the tapes, so as to secure the hoops to the tapes. The clasps D, it is believed, form a much firmer connection of the hoops to the tapes.

I do not claim, broadly, the employment or use of braids or cords crossed on the tapes and passing through the same and around the hoops, for they have been previously used; but,

Having thus described my invention, what I claim as new, and desire to secure by Letters Patent, is—

The braids or cords c , in combination with the clasps D, the above parts being applied to the tapes B, and all arranged as and for the purpose herein set forth.

L. SANDERS.
